UNITED STATES PATENT OFFICE.

JOSEPH MITERA, OF PLAINFIELD, NEW JERSEY.

MECHANICAL TOY.

1,389,372.

Specification of Letters Patent.

Patented Aug. 30, 1921.

Application filed January 15, 1921. Serial No. 437,402.

To all whom it may concern:

Be it known that I, JOSEPH MITERA, a citizen of Poland, residing at Plainfield, in the county of Middlesex and State of New Jersey, have invented certain new and useful Improvements in Mechanical Toys, of which the following is a specification.

The main object of this invention is the provision of a mechanical toy providing a number of dancing couples upon a platform which may be conveniently carried from place to place, and which may be regulated to start and stop at the will of the operator.

The above and other objects will become apparent in the description below, in which like-named characters of reference refer to like-named parts in the drawings.

Referring briefly to the drawings, Figure 1 is a plan view of the device, parts being broken away to disclose the construction.

Fig. 2 is an elevational view of the same.

Fig. 3 is a cross-sectional view on the line 3—3 of Fig. 1.

Fig. 4 is a side elevational view of the actuating spring used in the device.

Fig. 5 is a fragmentary sectional view of the ratchet and wheel the section being taken on line 5 of Fig. 3.

Fig. 6 is a cross-sectional view taken on the line 6—6 of Fig. 1.

Referring in detail to the drawings, the numeral 1 represents the base of the device, supported upon legs 2, and having a cylindrical casing 3 mounted thereon. A key 4, on the outside of the casing, is screwed upon the end of a horizontal shaft 5 having support in bearings 6. The shaft passes through a casing 7 supported by the base 1 and contains a coiled spring 8, the inner end of which is secured to the shaft and the outer end to the casing. A ratchet 9 is fixed to the shaft near its end, and a gear 10 is rotatably mounted upon the extremity of the shaft.

A pawl 11 pivoted on the gear is urged by a spring 12 into engagement with the ratchet 9.

A sleeve 13 is rotatably mounted circumjacent a vertical shaft 30 fixed in the base, and a bevel gear 31 rigid on the sleeve is in engagement with the gear 10. A spur gear 14 is carried by the sleeve 13, at its upper end and a stem extends upward therefrom through the platform 15 and a small circular platform 16 is rigidly secured upon

the upper end of the sleeve 13 above the gear 14 and platform 15.

Additional sleeves 17 provided with gears 18 similar to the gear 14, but of smaller diameter, and with platforms 19 similar to the platform 16, are provided in spaced relation concentrically, the gear 14 being in mesh with gears 18 and acting as a prime mover for them.

A horizontal shaft 23 is slidably mounted in supports 26 and 28 adjacent the underside of the platform 15, and is provided with a lug 22 extending upward through the platform 15. A cam-shaped member 24 is pivotally mounted at 25 on the platform adjacent the lug 22, and a coiled spring 27, surrounding the shaft 23 between the supports 26 and 28, normally presses the shaft 23 toward the central vertical shaft 30. In the periphery of the stem connecting the gear 14 with the platform 16, just beneath the platform 15, are provided a plurality of spaced recesses 20, adapted to be engaged by the extremity of the shaft 23. Upon each of the platforms 16 and 19 is rigidly mounted a miniature dancing couple.

The operation of the device is now apparent. Upon turning of the key 4 in a clockwise direction, the spring 8 will be wound up in the usual manner. During the winding up the shaft 23 lies in engagement with a recess 20, thus preventing turning of the gear 14 and therefore of the entire gear mechanism. After the spring has been wound up, the member 24 is moved outwardly its cam-like edge moving the lug 22, and causing the shaft 23, to be drawn out of engagement with the recess 20, and the mechanism begins to turn. By forcing the member 24 far enough toward the center the same may be wedged between the lug 22 and its pivot 25, thus retaining the same in released position. To stop the mechanism before the spring has become exhausted, the member 24 is freed from its retention whereupon the spring 27 draws the shaft into engagement with a recess 20. As is apparent, in operation all of the couples rotate about their own axes in addition to revolving about the center.

I claim:

A mechanical toy comprising a circular casing, a spring actuated clock work mech-

anism therein, a central vertical sleeve driven thereby, a plurality of like sleeves spaced concentric therewith, said concentric sleeves being geared to the central sleeve, 5 figural couples carried by all of said sleeves above said casing, a rod slidable in said casing, one end of said rod being engageable in recesses in said central sleeve, means

for normally causing such engagement, a lug on said rod projecting above said casing, and a manually operable cam pivoted on said casing adapted to engage said lug to withdraw it from the mentioned recesses thereby permitting rotation of said couples.

In witness whereof I affix my signature. 15
JOSEPH MITERA.
